UNITED STATES PATENT OFFICE.

ALLISTER STEWART MITCHELL, OF OAKLAND, CALIFORNIA, ASSIGNOR TO CALIFORNIA COTTON MILLS COMPANY, OF OAKLAND, CALIFORNIA, A CORPORATION OF CALIFORNIA.

FLEXIBLE TOOL.

Application filed September 20, 1923. Serial No. 663,834.

To all whom it may concern:

Be it known that I, ALLISTER STEWART MITCHELL, a citizen of the United States, residing at Oakland, in the county of Alameda and State of California, have invented certain new and useful Improvements in Flexible Tools, of which the following is a specification.

My invention is an improved apparatus 10 for forming upholstery.

The method of using this type of apparatus has already been described in my co-pending applications Serial Numbers 609,608 and 622,900.

15 The object of my present invention is to provide an apparatus of this character which is inexpensive to manufacture and efficient in operation.

A further object is to provide an apparatus 20 which is split transversely and will yield to conform to the shape of the pipes in the seat back, and which is provided with cutting edges at the end thereof to sever the padding.

25 Further objects and advantages will be more particularly pointed out in the following detailed description.

In the annexed drawing in which my invention is illustrated:

30 Figure 1 is a plan view partly in section of my apparatus inserted into a seat back.

Figure 2 is a plan view of my apparatus in its normal position.

Figure 3 is a plan view of my apparatus 35 in the closed position.

Figure 4 is a sectional view taken on the line 4—4 of Figure 2.

Referring more particularly to the drawing, my invention comprises a tube 1 which 40 is preferably cut away at one end so as to form the points 2 with the space 3 between them. The tube is split throughout its length to form the two sections 4 and 5 which overlap throughout the greater part 45 of their length. One end of the sections 4 and 5 is flared outwardly as at 6 and 7 respectively to form a mouth for the reception of the padding.

As a means of holding the sections 4 and 5 50 apart I have provided a spring wire 8 to which the flared parts 6 and 7 are secured and which encircles the mouth of the tube. When the sections 4 and 5 are compressed the wire 8 will bend and as promptly as the 55 sections are released will return them to

their normal position. A collar 9 is secured to the section 5 and encircles the section 4, thus acting as a stop to limit the outward movement of the sections. The outer adjoining edges 10 and 11 of the sections 4 and 5 60 respectively are sharpened and when the sections are compressed act as scissors to cut the padding.

In the use of the device the filling 12 is made up in long pieces. They can be any 65 desired length. This filling may be of any desired form and may be made of any desired material, such as cotton. With this device it does not have to be reenforced in any manner. In the use of the device the end of 70 the strip 12 is inserted when the sections are expanded, thus giving plenty of room for this insertion. The material is inserted so as to fill the tube. The tube is then grasped by the hand preferably near the lower end 75 and squeezed so as to bring the sections 4 and 5 in their contracted position. The end of the tube is then inserted in one of the tubes and the tube pushed completely into the pipe. The operator then takes his 80 thumb and finger and presses the cover of the cushion at the point where the slot 3 in the tube is located, thus holding the filling 12. The holder is then withdrawn and slides along the strip 12 of filling material 85 until the end is reached. The filling material is then placed between the cutting edges 10 and 11 and severed by compressing the sections 4 and 5.

Having described my invention, I claim: 90

1. An apparatus for forming upholstery comprising a tube for the filling material consisting of two sections placed side by side and overlapping, said sections adapted to be moved relatively to compress the filling therein so that it may be inserted in the upholstery tube, and a spring wire to which the ends of said section are secured and adapted to normally move them to their expanded position when the tube is released. 95

2. An apparatus for forming upholstery comprising a tube for the filling material consisting of two sections placed side by side and overlapping, said sections adapted to be moved relatively to compress the filling therein so that it may be inserted in the upholstery tube, a spring wire to which the ends of said section are secured and adapted to normally move them to their expanded position when the tube is released, and a 100 105 110

collar formed on one of said sections and surrounding the other section to limit the expansion of said sections.

3. An apparatus for forming upholstery comprising a tube for the filling material consisting of two sections placed side by side and overlapping, said sections adapted to be moved relatively to compress the filling therein so that it may be inserted in the upholstery tube, a spring wire to which the

ends of said section are secured and adapted to normally move them to their expanded position when the tube is released, the outer ends of said sections being cut away to form a space there between and the adjoining edges of said space being sharpened to form a cutting edge.

In testimony whereof I affix my signature.

ALLISTER STEWART MITCHELL.
